UNITED STATES PATENT OFFICE.

DAVIS GRAY AND JOSIAH GRAY, OF WAYLAND, NEW YORK.

IMPROVEMENT IN AXLE-SKEINS.

Specification forming part of Letters Patent No. 35,676, dated June 24, 1862.

To all whom it may concern:

Be it known that we, DAVIS GRAY and JOSIAH GRAY, of Wayland, Steuben county, State of New York, have invented certain new and useful Improvements in Axle-Skeins, of which the following is a full, clear, and exact description, reference being had to the accompanying drawings, forming part of this specification, in which—

Figure 1 represents a perspective view of an axle-skein embracing our improvements. Fig. 2 represents a longitudinal section through the same.

Our improvements relate to that class of axle-skeins known as the "tubular skein," in which the wooden axle enters and is completely surrounded by the skein. Skeins of this description are made of cast-iron, brass, or steel plates bent in the form of a tube and welded or brazed on the upper surface. Those made of the latter material are considered superior to all others, owing to their being lighter, stronger, and more durable, and also from their running with less friction in the cast-iron box than those made of other metals.

Various forms have, we are aware, been given to the tubular axle-skein, and among others that of finishing the inner end square or beveling it off, so as to form a projecting tongue on the under side. These skeins are generally confined to the axle by the hub-bolt entering the end of the axle, or by one or more bolts passing in a transverse direction through the inner end of the skein and the axle, or by two bolts and a clasp or band. These modes of attaching the skein weaken the axle and render it liable to split or break at the point the bolt enters or passes through it.

To remedy this defect, and attach the skein securely to the axle without weakening it or using other bolts or bands than those necessary to connect the different parts of the carriage, is the object of our improvement, which consists in making the skein of a cast-steel plate with the inner end beveled off to form a projecting tongue on the under side, and sufficiently thin to yield readily to compression, and then confining it to the axle by the

same clips which attach the arms or reach to the axle.

In the accompanying drawings is represented an axle to which a skein embracing our improvements is attached, which consists of a thin plate of steel bent into a slightly-tapering cylindrical form and welded or brazed on the upper side.

To the outer or small end of the cylinder is welded a plug, A, on which a screw is cut for a nut to confine the wheel to the axle. At a proper distance from the outer end a ring, b, is welded to the skein, forming a collar for the inner bearing to the axle-box. The inner end of the skein is sloped from the upper to the under side, (and may be drawn down, if thought best,) and is thus prolonged on the under side some distance beyond the upper, in order to give increased support to the axle and greater permanency to the attachment of the skein to the axle. The skein is then driven on the end of a wooden axle fitted to receive it, and confined by the arm or reach-clip B, which is bent to conform to the axle just inside the re-entering angle on the top of the skein. The sides of the clip embrace the side of the axle and also the side of the projecting tongue of the skein, and the clip-bolts are also bent inward and pass through holes in the clip-plate C, which is also bent to conform to the under side of the projecting point of the skein, on which it bears.

The clip is arranged on the axle so that the upper part bears on the wood just inside the re-entering angle of the skein, while the side and bottom plate embrace the projecting tongue of the plate. In screwing up the clip the tongue of the skein is compressed and caused to bind closely to the wood of the axle, by which means it is held securely to the axle without additional bolts or fastenings.

In fastening the skein to the axle by means of the clip the expense of additional bolts is saved, and the axle is not weakened by bolt-holes; and, moreover, the strain of the clip-bolts causes the projecting end of the skein to spring and adapt itself closely to the wood of the axle, thus giving great strength and per-

maneney to the attachment of the skein to the axle.

Having thus described our improvement in steel skeins, what we claim as new, and desire to secure by Letters Patent, is—

The combination of a hollow steel axle-skein constructed substantially as described, with the arm or reach-clip so constructed and

arranged on the axle as to grasp and compress the sides of the skein, and thus hold it firmly to the axle.

DAVIS GRAY.
JOSIAH GRAY.
